HOOD FOR INFANTS' CARRIAGES

William C. Troendle, Gardner, Mass., assignor to
Thayer Company, Gardner, Mass., a corpora-
tion of Massachusetts

Application September 17, 1941, Serial No. 411,193

10 Claims. (Cl. 296—112)

This invention relates to a new and improved fixture construction for hoods for infants' carriages.

The principal object of the invention is to provide an easily operable means to both simultaneously break and close the hood fixtures for the purpose of single-handedly folding or extending the hood.

Other objects of the invention include the provision of an attachment connected to corresponding elements of an infant's carriage folding hood fixture at both sides of the hood to permit simultaneous manual operation of the fixture locking means; the provision of a handle for simultaneously breaking or closing the fixtures of a hood, said handle also having the further function of serving as a bumper for the rear end of the carriage to which it is attached; and the provision of a combined carriage bumper and folding hood operating means.

Other objects and advantages of the invention will appear hereinafter.

Reference is to be had to the accompanying drawings, in which

Fig. 1 is a side elevation of an infant's carriage showing an embodiment of the invention applied thereto with the hood extended;

Fig. 2 is an enlarged side elevation of the hood in partly extended condition, with the carriage broken away;

Fig. 3 is an enlarged side elevation of the hood folded with the carriage broken away; and

Fig. 4 is an enlarged top plan view of the hood per se in extended condition.

The conventional infant's carriage of the type disclosed is ordinarily provided with a folding hood generally indicated at 1 in Fig. 1. Such hoods are held in extended condition by means of a lever 2 pivoted to a bottom bow element 3 and fixed to a joint 4, there being a link 5 pivoted to the joint and to the top bow element 6. When lever 2 and link 5 are extended generally upwardly past dead center as illustrated in Fig. 1, the tension of the hood covering material is such as to hold the parts in their extended condition. When it is desired to fold the hood to a condition as shown in Fig. 3, it has been necessary in the prior art to break the joint at each side of the hood separately to allow pivoting rearwardly of the bow elements. This is an awkward procedure especially with an occupant in the carriage 7, which is here shown as mounted on a frame 8 having wheels 9.

In the particular embodiment shown, the carriage 7 is provided with a top rail 10 to which is

detachably secured at each side a bracket 11, only one being illustrated. A pin 12 on the bracket provides a pivot support for the various bow elements, there being any desired number of the latter. At the rear of the hood a snap strap 13 holds the bottom bow element 3 to the rail 10, so that a three point attachment of the hood to the carriage is provided.

Lever 2 is pivoted at one end by means of pin 14 to bottom bow element 3, and at its other end it is fixed by a pair of rivets to the joint 4. Link 5 is pivoted to the top bow element at one end and to the joint 4 at its other end. Hence pivoting downwardly of lever 2 will carry with it the joint and will cause link 5 to pivot in a clockwise direction about its pivot connection to the joint, thus folding the hood.

A generally U-shaped rod 15 having a twisted handle portion 16 centrally of its closed end is arranged to pivot on pins 14 beneath corresponding levers 2. The open ends of the legs of rod 15 are bent out of the plane of the rod and pins 14 extend thru the rod legs just forwardly of the bends. At these pivot points and also at the pivot points of links 5 with bow elements 6, the rod legs and links are curved away from the hood for clearance, as at 17, this relation being somewhat exaggerated in Fig. 4 for clarity in illustration.

30 The bent portions of the rod legs are indicated at 18, and these portions are arranged to lie parallel and closely adjacent to the corresponding levers 2. Clips 19 of any desired or convenient conformation surround the free end of portions 18 and the levers to secure the parts rigidly together forwardly of the pivot pins 14, the latter preventing any tendency of the parts to twist in the clips.

With the hood in extended position, see Figs. 40 1 and 4, the rod 15 extends rearwardly of the carriage and acts as a bumper. When it is desired to fold the hood, the handle portion 16 of rod 15 is grasped in one hand and lifted, or in other words, rod 15 is pivoted counterclockwise 45 in the direction of the arrow in Fig. 2. By reason of the fact that the rod legs and levers 2 are rigidly connected by clips 19 and pivot pins 14, the joint 4 is forced counterclockwise and thus passes dead center to the position of Fig. 2, bringing top bow element 6 rearwardly about pin 12 and folding the hood section adjacent bottom bow element 3 along the broken line in this figure. The top bow element 6 may now be pushed down and rearwardly to completely 50 folded condition of the hood, see Fig. 3, the bro-

ken lines in this figure indicating folded hood material.

Upon reversal of the above procedure, to extend the hood, the top bow element may be easily raised to approximately Fig. 2 position, and then a downward or clockwise push on handle 16 will force the levers and links to locked position past dead center to achieve the Fig. 1 condition.

It will be seen that the above described construction provides a simple and inexpensive means to simultaneously break both joints for folding, and conversely will provide for again locking the hood in extended position without detriment to the holding action of the levers and links, and without interference with the folded condition of the hood.

Having thus described my invention and the advantages thereof, I do not wish to be limited to the details herein disclosed, otherwise than as set forth in the claims, but what I claim is:

1. In a device of the class described, a folding, extensible hood, a series of interpivoted elements defining said hood in its extended condition, a pair of separate linkages secured in pivoting relation to certain of said elements and adapted to be moved past a dead center to hold said hood extended and to permit folding thereof, means secured in fixed relation to corresponding members of said linkage to simultaneously move the same past said dead center in either direction, said means comprising a pair of legs secured to said corresponding members, and a bar extending between said legs, said bar forming both a handle and a bumper and being spaced from the hood.

2. In a device of the class described, a foldable, extensible hood, a series of interpivoted elements defining said hood in its extended condition, a pair of levers pivoted to one of said elements, a pair of links pivoted to another of said elements, and each lever being pivoted to a link, whereby pivotal movement of said levers in one direction will cause extension of said hood, and a rigid member secured to both levers for simultaneous operation thereof, said member being pivoted to said hood at its sides, and extending completely around the rear of the hood in the general form of a U.

3. A device as recited in a claim 2 wherein pivotal movement past a dead center will lock said hood in extended condition, and wherein said member is adapted to pivot said levers in either direction, to lock and unlock said hood depending on the direction of lever movement.

4. In a device of the class described, a foldable, extensible hood, a pair of interpivoted elements secured to opposite ends of the hood, a pair of separate links pivoted to one element, a pair of levers pivoted to the other element, each link being pivoted to a lever, each pivoted link and lever forming means to support said hood in extended condition, and a rigid connection between said levers for simultaneous pivotal movement of said levers in either direction, said connection being pivoted to the hood on an offset axis.

5. A device as recited in claim 4, wherein said connection extends past one end of the hood to act as a bumper as well as a handle.

6. In an infant's carriage, a folding, extensible hood mounted adjacent one end of the carriage, a pair of bow elements secured to opposite ends of said hood, said elements being interpivoted for folding or extending said hood, a pair of links pivoted to one element, a pair of levers pivoted to the other element, and a pivot connection between each lever and a corresponding link, said links and levers forming spaced linkages at each side of the hood to hold it in extended condition, and a generally U-shaped bar pivoted with the levers and secured thereto adjacent its ends, the closed portion of the U-shaped bar extending normally rearwardly beyond the carriage and hood to act as a bumper.

7. In a device of the class described, an extensible hood and a pair of levers at each side of the hood, each pair of levers being interpivoted at adjacent ends and having their opposite ends pivoted to end members of the hood, a U-shaped bar extending around a portion of the hood, the legs of the member being secured to corresponding levers for movement therewith, said member providing a single means for pivoting said corresponding levers.

8. In a device of the class described, an extensible hood having a pair of pivoted bows for collapsing and extending the hood, a pair of levers pivoted at their ends to one bow at opposite sides of the hood, a pair of levers pivoted at their ends to the other bow at opposite sides of the hood, the levers at corresponding sides of the hood being interpivoted, a U-shaped bar pivoted adjacent its ends to one of said bows and having rigid connections with one of said pairs of levers for movement therewith, said bar extending exteriorly of the hood and providing means to actuate the pair of levers connected thereto.

9. In a device of the class described, an extensible hood having a front bow and a rear bow, the latter being adapted to be secured in fixed relation to a carriage, said bows being interpivoted for extending and collapsing the hood from and to said rear bow, a pivot at each side of said rear bow, means for latching the hood in extended condition pivotally mounted on said pivot, a bar extending rearwardly of the hood and completely across the hood, said bar being pivoted at its ends on said pivots, a rigid connection between said bar and said means, whereby movement of said bar correspondingly moves said means to and from a hood-latching position.

10. In a device of the class described, an extensible hood having a pair of U-shaped bows pivoted together at their ends, one bow being adapted to extend generally vertically and the other horizontally in extended condition of the hood, and said one bow being adapted to pivot backwardly onto said other bow to collapse the hood, a pair of interpivoted levers at each side of the hood, one lever of each pair being pivoted to the one bow and one lever of each pair being pivoted to the other bow, a U-shaped bar extending outwardly beyond the said other bow and being pivoted thereto, said bar being secured rigidly to the levers pivoted to said other bow, so that movement of said bar will effect pivotal movement of the levers connected thereto.

WILLIAM C. TROENDLE.
